DRY BATTERY

Application filed April 10, 1928. Serial No. 268,875.

This invention relates to dry batteries of the type employing a so-called "bobbin" consisting of a mass of depolarizing material molded about a carbon rod which is adapted to function as an electrode, the depolarizing material being enclosed within a bibulous envelope of suitable material, such as a wrapper of cheese cloth.

The general objects of this invention are to provide simple and reliable means for securing the wrapper in place about the depolarizing material, and also to provide simple and reliable spacing means for facilitating centralizing the bobbin within its container during the assembling and for thereafter maintaining the bobbin properly spaced from the wall of its container.

The invention will be understood from the following description taken in connection with the accompanying drawings, in which Figure 1 is a side elevation of a bobbin embodying this invention, showing also the container for the bobbin, the latter being in vertical section; Figure 2 is a plan view of the bobbin except that a disc of insulating material at the top of the bobbin is omitted; Figure 3 is a bottom view of the bobbin; and Figure 4 is a view similar to Figure 1 but showing a modified form of means for securing the envelope in place thereon.

In the drawings the usual zinc container 5 is indicated as having a cylindrical side or wall 6 and a bottom 7 soldered thereto. The bobbin is shown as including a carbon rod 8, having a metal cap 9, and a cylindrical body of depolarizing material 10 molded about the rod. The molded depolarizing material 10 is confined within a suitable envelope, such as a wrapping of cheese cloth 11, the longitudinal margins of which overlap each other, as shown in Figures 1 and 4, and the upper and lower ends of which are folded inwardly over opposite ends of the depolarizing material. The folded portions 12 at the bottom of the depolarizing material 10 overlap each other, as indicated in Figure 3, and are held in a proper relation to each other by a suitable material, such as a coating of paraffin, not shown.

50 Around the depolarizing material 10 and

in close engagement with the envelope carried thereby, are a pair of spacing elements. These spacing elements are in the form of cords 15 which are spaced from each other and are of such lengths, respectively, that their opposite ends overlap to an appreciable extent. The overlapping ends of the cords 15 are secured together by a suitable material, such as sealing wax, 16, which is applied while in a melted condition so as to enable it to closely adhere to the overlapping ends, whereby such ends are effectively united to each other. These cords 15 are relatively large in cross section, and serve to center the bobbin as it is introduced into its container 5 and also serve to thereafter maintain the bobbin properly spaced from the wall of its container.

Referring to Figures 1 to 3 inclusive, the folds 12 of the cheese cloth 11 at the upper end of the bobbin are united to each other by a coating of suitable material, such as paraffin not shown, and are held in a flat condition about the carbon electrode 8 and in a fixed relation with respect to each other by a washer 18 of insulating material, such as cardboard which encircles and frictionally engages the carbon electrode 8, so that it may be maintained in firm engagement with the folds 12 of the envelope at the upper end of the depolarizing material when it is pushed down over the carbon electrode before the metal cap 9 is applied thereto. The washer 18 is preferably coated with a suitable material, such as paraffin not shown, whereby the washer is rendered impervious to moisture, as will be readily understood.

Referring to Figure 4, wherein is shown a modified form of the invention, the folds 12 of the cheese cloth 11 at the upper end of the depolarizing material 10 form a neck 20, surrounding the carbon electrode 8, about which a cord 21 is wrapped. This cord serves to hold the neck 20 of the cheese cloth in close engagement with the carbon electrode 8, and is preferably secured in position, by wrapping the last few turns of the cord over the remaining turns of the cord while under sufficient tension to imbed such last few turns of the cord into the remaining turns, thereby obviating the necessity of knotting or other-

wise similarly tying the ends of the cord together. If desired, the cord 21 may be coated with a suitable adhesive so as to effect its intimate union with the neck 20 and to also effect intimate union of the several turns of the cord with each other.

While certain embodiments of the invention are herein shown, it will be understood that various changes may be made with respect thereto without departing from the spirit of the invention or the scope of the following claims.

What is claimed is:

1. A battery bobbin comprising an electrode having depolarizing material surrounding the same, and a cord surrounding said depolarizing material and serving as a spacing member, said cord having its opposite ends overlapping each other and adhesively united to each other.
2. A battery bobbin comprising an electrode having depolarizing material surrounding the same, and a plurality of cords surrounding said depolarizing material in a spaced relation to each other and having their respective opposite ends overlapping and adhesively united to each other.

In testimony whereof, we have affixed our signatures to this specification.

MAX ZERNER.
OTTO KARL REINHARDT.
